UNITED STATES PATENT OFFICE

BRUNO A. POLLAND, OF OMAHA, NEBRASKA

BATTERY-BOX HOLDDOWN

Application filed April 16, 1928. Serial No. 270,497.

This invention relates to a battery-box holddown, and has for its principal object to provide a bracket or holder of such construction that its metallic parts will be disposed below the top of the box in order that corrosion will be avoided.

Another object is to provide a holder which will so stabilize the battery that undue vibration will be prevented.

Still another object is to provide a holder which will be convenient in use, and will permit convenient removal of the battery whenever required.

It is also an object to provide such a construction that the holder will consist of few and simple parts so that it may be manufactured at a limited cost.

With the foregoing objects in view the invention presents a new and useful construction, combination and arrangement of parts as described herein and claimed, and as illustrated in the accompanying drawings, it being understood that changes may be made in form, size, proportion and minor details, said changes being determined by the scope of the invention as claimed.

In the drawing, Fig. 1 is a perspective view showing the holder secured to a support.

Fig. 2 is a view similar to that shown in Fig. 1, a battery being added and supported by the holder. Fig. 3 is a detail showing co-operating elements for connecting two of the arms or bands of the holder.

Referring now to the drawing for a more particular description, the invention is shown and described in connection with a support 4 or part of the frame of an automobile, and numeral 5 indicates the battery box, these parts being conventional and requiring no description, except to state that the acid which generally exudes from the cells cause corrosion of any metallic parts which are exposed.

The battery boxes generally used are constructed of vulcanized india rubber to prevent corrosion but it will be appreciated that "stay-downs" or hold downs which grip the top of the box will be exposed to the action of the acid. These "stay-down" devices are generally constructed of attenuated strips to avoid weight and become injured and often are destroyed by action of the acid.

It will be seen that in its present embodiment of the invention no metallic parts are disposed at the top of the box.

The invention consists of an upright supporting-plate 6 approximately of T-shape adapted to be secured to said member 4 by any suitable means, as by use of keepers 7. The bottom of this plate is provided with a sheath 8 of angular form in cross-section.

Numerals 9 indicate a pair of L-shaped bands. They are maintained in a horizontal position by hinges 10 which connect one of the ends of each band to the ends of the arms 11 of the T shaped plate 6, and on account of their hinged mounting said bands 9 may have limited horizontal swinging movements.

Since battery boxes generally have a form rectangular in plan the sheath 8 is of similar form, its upright flange 12 being adapted to engage the sides and its horizontal flange 13 being adapted to engage the bottom of the box.

I provide fastening devices which co-operate in operation for pressing the bands 9 firmly against the sides of the box, as the latch 14 which is secured to one of said bands, and the thumb-catch 15 which is secured to the other band 9 said catch being pivotally mounted on its band 9 as indicated at 16, and the latch being pivotally mounted on said catch as indicated at 17.

It will be understood that since the battery boxes are of standard size the L-shaped arms and fastening devices may be of such proportions that the bands 9 will be pressed firmly against the sides of the box when the catch has been moved to position shown in solid lines in Fig. 3, and the sheath is of such proportions that the box will snugly fit therein when the box is mounted in the bracket.

In operation, the box may be readily removed. The catch may be swung outwardly to the position shown by dotted lines in Fig. 3, which forcibly moves the bands 9 outwardly from the sides of the box. Since the battery requires frequent replacements this feature will be appreciated. To mount the battery in operative position, it is lowered down into the sheath and the catch is then swung so that its handle will engage the band 9 on which it is mounted, and since this swinging

movement will carry the pivotal mounting 17 of the latch inwardly of the pivotal mounting 16 of the catch, the catch will maintain the parts in locked relation until the handle of said catch has been forcibly swung outwardly.

It will be seen that the plate 6 is of such proportions that the battery will project an appreciable distance above its upper edge, 10 and since the sheath and bands 9 are disposed at right-angles to said plate 9 these metallic parts will not be exposed to the action of the acid at the top of said box and this is an important feature. By use of the invention the bands may be of attenuated form so that they will not add appreciably to the weight of the vehicle, and since the sheath closely engages the lower parts of the box its form may be attenuated.

20 I claim as my invention,—

1. In a battery box holddown, an upright supporting-plate approximately of T-shape provided at its lower end with a horizontal sheath for engaging the sides and bottom 25 of the battery box, its upper end being provided with a pair of L-shaped bands hingeably mounted on the supporting-plate below the top of said box, and co-operating fastening elements on said bands for pressing said bands toward each other into engagement with said box.

2. In a battery box holddown, an upright supporting-plate of T-shape having a sheath at its bottom projecting at right-angles therefrom for engaging the sides and bottom of 35 the box when seated therein, a pair of bands hingeably mounted upon and disposed parallel with said sheath for engaging the sides of the box below the top thereof, and means 40 for pressing said bars against the sides of the box.

3. In a battery box holddown, a supporting-plate approximately of T-shape having a sheath extending at right angles thereto for 45 receiving the lower part of the box, a pair of bands hinged to said plate and disposed above the sheath and approximately parallel with said sheath, and cooperating fastening devices for pressing said bands against the 50 sides of said box.

4. In a battery box holddown, an upright supporting-plate engaging one side and having a lesser height than the height of the box and having a sheath extending outwardly 55 from its bottom at right-angles from said plate for engaging the sides and bottom of the box, a pair of arms disposed between the top and bottom of the box parallel with the sheath and hinged to said plate, and co-operating fastening elements mounted on said 60 bands for pressing them against said box.

5. In a battery box holddown, an upright metallic supporting-plate approximately of T-shape having a sheath extending at right-angles 65 from its lower end for engaging parts

of the bottom and sides of the box, a pair of metallic bands disposed above and parallel with the sheath each being hinged to the plate to permit it to be swung inwardly and outwardly from opposed sides of the box below the top of said box, and co-operating fastening elements mounted on said bands for pressing them into engagement with said box.

6. A battery support comprising a vertical attaching plate having oppositely extending horizontal arms at its upper end lying in the same plane with the plate, a substantially rectangular open frame carried by the lower end of the plate and at approximately right angles to the plane of the plate, said frame having horizontal and vertical flanges to receive the bottom and side portion of the battery, L-shaped bands hinged at one end to the outer ends of the horizontal arms and embracing the sides and front of the battery below the top thereof, and means for opening and closing the hinged bands upon the battery.

In testimony whereof, I have affixed my signature.

BRUNO A. POLLAND.
